(57) **CLAIM**

The ornamental design for a container for icing, as shown and described.

DESCRIPTION

FIG. 1 is a top, side and front perspective view of a container for icing showing my new design;

FIG. 2 is a front elevation view thereof, the rear elevation being identical thereto;

FIG. 3 is a right side elevation view thereof, the left side elevation being identical thereto;

FIG. 4 is a top plan view thereof;

FIG. 5 is a bottom plan view thereof; and,

FIG. 6 is an exploded view of the container for icing shown in FIG. 1.
